UNITED STATES PATENT OFFICE.

ALBERT T. DERBY, OF SAN FRANCISCO, CALIFORNIA.

ATTACHMENT FOR AUTOMATIC PIANO OR ORGAN PLAYERS.

SPECIFICATION forming part of Letters Patent No. 687,559, dated November 26, 1901.

Application filed May 22, 1901. Serial No. 61,334. (No model.)

To all whom it may concern:

Be it known that I, ALBERT T. DERBY, a citizen of the United States, residing in the city and county of San Francisco, State of California, have invented an Improvement in Attachments for Automatic Piano or Organ Players; and I hereby declare the following to be a full, clear, and exact description of the same.

10 My invention relates to improvements in self-playing attachments for pianos and organs wherein the keys are operated by suitable mechanism through the medium of air-currents passing through perforations in a 15 movable sheet of paper.

It has particular relation to that form of instrument popularly designated as a "pianola." In these instruments the tracker-board and music-rolls are contained in a central recess, and these parts are ordinarily unin- 20 closed during the process of playing in order that the levers governing the "tempo," "ex- 25 pression," &c., may be manipulated and the expression-marks on the roll read. In all the 30 self-players of this type the sound of the suc- 35 tion of the air through the tubes in the tracker-board and the scraping of the paper in its passage over the tracker-board greatly 40 mar the otherwise musical tones of the in- strument. This is particularly noticeable in 45 pianissimo-playing.

It is one object of my invention to muffle 50 these disagreeable sounds and still allow access to the parts for the necessary change of 55 rolls and permit the marks of expression to be seen, yet without in any way interfering with 60 the proper management of the above-men- 65 tioned levers.

Another object of my invention is to fur- 70 nish a means of positively operating the 75 "soft" pedal. In the pianola, to which, as 80 before stated, my improvements have par- 85 ticular reference, the "loud" pedal only has 90 been under the control of the operator, the 95 pianissimo effects depending on the shortening 100 of the stroke of the fingers on the keys, while in other self-players in which the soft 105 pedal has been called into requisition it has 110 in all instances of which I am aware been 115 operated by pneumatics. The value of tone- 120 shading by means of the pedals is obvious, 125 and it has been my purpose to add to the in-

strument herein designated as the "pianola" 130 the means of bringing the soft pedal directly 135 under the operator's control and using it 140 either in substitution of or in conjunction 145 with the present means of acquiring the 150 lighter shades of tone.

Having reference to the accompanying 155 drawings, Figure 1 is an end view and partial 160 section of the instrument. Fig. 2 is a per- 165 spective view of the same.

A represents the casing of an instrument 170 of the ordinary pianola type in which the 175 fingers operating the keys of the piano or or- 180 gan are actuated by pneumatic devices and 185 with which this invention has no relation.

2 is a central recess in which the tracker- 190 board 3 and the rolls 4 are contained. Oper- 195 ating in a slot 5 in the bottom of this recess 200 is a series of levers 6 7 8 9, respectively gov- 205 erning the loud pedal, the "piano," tempo, 210 and the rewinding mechanism. Hinged upon 215 the rear wall of the recess is the glazed cover 220 10. The glass of this cover is held in a curved 225 metal sash 11, conforming generally to the 230 contour of the casing A and resting on the 235 bottom of the recess rearward of the levers 240 6 7, &c. In order to permit the cover so to 245 fit, the levers are bent outwardly at approxi- 250 mately right angles upon themselves, as 255 shown. The front and lower portion of this 260 sash is provided with the flanges 12, and the 265 outer edges of these flanges are connected by 270 a horizontal bar 13. 275

The ledge 14, upon which the cover rests, is 280 provided with a felt, rubber, or equivalent 285 lining, which serves entirely to muffle the 290 sounds of the indrawing air through the per- 295 forations in the paper and of the scraping of 300 the latter as it travels over the tracker-board. 305 The result is the elimination entirely of this 310 disagreeable feature referred to and the giv- 315 ing full effect to the sweetest and lowest tones 320 of the instrument. 325

By means of the bar 13 the cover is lifted 330 at any time when it is desired to have access 335 to the rolls, and a stop 15 on the casing A 340 limits the backward movement of the cover. 345

The cover not only serves to exclude the 350 dust at all times and to muffle the said un- 355 musical sounds, but to add materially to the 360 finished appearance of the instrument.

The second part of my invention relates to

connecting the lever 7, controlling the piano, directly with the soft pedal. This I do preferably in the following manner: In Fig. 2 the lever 7 is shown fulcrumed at 16. The 5 lower end of the lever controls the present piano mechanism heretofore referred to. A rod 18 connects the lever 7 with one arm of a bell-crank lever 19. The other end of the bell-crank lever connects with a rod 20, which 10 joins an arm 21 on a rock-shaft 22, disposed longitudinally of the machine. Adjustably secured upon this rock-shaft is the outwardly and downwardly curved arm 23, which is adapted to bear upon the soft pedal 24. The 15 latter is operated by the movement of the lever 7 and by the oscillation of the shaft 22.

Having thus described my invention, what I claim as new, and desire to secure by Letters Patent, is—

20 1. The combination in an automatic piano-player of a casing having a recess, a tracker-board and music-sheet-winding mechanism contained in said recess said casing having horizontal slots at the front lower portion of 25 the recess, levers in the casing below the recess and having their upper ends passing through said slots, and bent outwardly, and a glazed cover hinged to the rear wall of the recess and adapted to inclose said tracker-board and music-sheet-winding mechanism 30 and exclude said levers.

2. The combination in an automatic piano-player of a casing having a recess said casing having slots in a horizontal portion at the 35 base of the recess, vertically-disposed levers disposed below the recess and having their

upper ends passing through said slots and turned outwardly, a glazed cover for the recess, hinged to the rear wall thereof and having an arched form and inclosing the tracker- 40 board and music-sheet-winding mechanism, said cover having a substantially vertical front wall adapted to rest upon the bottom of the recess back of the slots.

3. In an automatic piano-player, the combination 45 of a casing, having a recess, a tracker-board and music-sheet-winding mechanism contained in the recess said casing having horizontal slots at the base of the recess, levers disposed vertically in the casing below the recess and having their ends extending through the slots and turned outwardly, a glazed cover, hinged to the rear wall of the recess and having its front substantially vertical and with the bottom edge 50 resting upon the bottom of the recess and means for operating one of said levers having a positive connection with one, only, of the pedals said connection including a rod extending from one end of the lever, a bell-crank lever connecting with the opposite end of the rod, a second rod extending from the bell-crank lever, and a rock-shaft, disposed 55 horizontally and connected to the second-named rod said rock-shaft having an arm to 60 bear upon the soft pedal.

In witness whereof I have hereunto set my hand.

ALBERT T. DERBY.
